Attorneys

UNITED STATES PATENT OFFICE.

JOHN R. MITCHELL, OF WHEELWRIGHT, KENTUCKY.

CLOTHES WASHER.

Application filed June 18, 1923. Serial No. 646,182.

To all whom it may concern:

Be it known that I, JOHN R. MITCHELL, a subject of the King of Great Britain, residing at Wheelwright, in the county of 5 Floyd and State of Kentucky, have invented certain new and useful Improvements in Clothes Washers, of which the following is a specification.

The present invention relates to devices 10 for washing clothes and more particularly to such adapted to be manually moved up and down and guided in such a manner as to cleanse the clothes by the circulation of water, and cleansing material, such as soap, 15 and by the pressure and suction upon the clothes incident to the up and down movement of the device.

The principal objects of the invention are, 20 to provide clothes washers which are adapted to readily receive and carry soap in cake or chipped form, or powdered soap in a suitable sack or other container previous to water; to provide devices with ways there-through whereby the water in which the 25 clothes are washed may find its way through the devices about the soap therein and thus thoroughly distribute and circulate the cleansing medium; and, to provide such devices which are inexpensive to manufacture, 30 capable of withstanding the forces coming upon them, and not liable to injure the clothes which they engage when in use.

Other objects and advantages of the invention will appear in the following detailed description, taken in connection with the accompanying drawings, forming a part 35 of this specification, and in which drawings—

Figure 1 is a view in elevation of a 40 clothes washer constructed according to the present invention.

Fig. 2 is a central vertical sectional view 45 through the head of the washer as positioned when it is desired to introduce soap thereinto, a portion of the handle being shown in part elevation and part section.

Fig. 3 is a bottom plan view of the washer.

Fig. 4 is a cross sectional view on the line 50 4—4 of Figure 1.

In the drawings where similar characters 55 designate corresponding parts throughout the views, A designates a handle and B the head of the washer including a main body portion C, preferably a frusto-conical shell,

an attaching collar D for the handle A, and a transverse partition E provided with a detachable closure F which permits of the introduction of soap into a compartment G defined in the main body portion C by the 60 partition E.

The handle A may be made of wood of a length convenient to be grasped by the user and in the example shown has its one end portion reduced as at 5 for insertion into 65 the collar D where it may be secured as by rivets 6, the handle being coaxial with the head B.

Referring now more particularly to the head B the mouth of the main body portion 70 C is preferably rounded off as at 7, such as by turning the metal, from which it is formed, upon itself, so as to present no cutting edge for engagement with the clothes. The partition E may be secured in the main 75 body portion C in any suitable manner, such as by soldering or welding and in the example shown is provided with an outwardly flaring flange 8 secured to body C as by rivets 9. This flange not only serves as 80 a securing means for the partition but also serves to strengthen the main body portion and retain it in proper shape. The partition E is so positioned that the compartment G is of ample size to receive a cake 85 of soap or a portion thereof with ample room for it to move about, access to the compartment being gained through an opening 10, which, when in use is closed by a cap or other closure F. The opening 10 90 may be bounded by an outwardly extending annular flange 11 with which the cap F has screw threaded engagement. Partition E is provided with a plurality of perforations 95 12 preferably located in uniform spaced apart relation from each other and with respect to the axis of the head, while the main body portion C is provided with a plurality of transverse perforations 13 open to the compartment G, these perforations 13 being 100 preferably located adjacent the partition E, so that in use ways for the water used when washing may pass to and from the compartment G through these perforations 12 and 13. It is preferred to locate the perforations 12 and 13 in staggered relation, so to speak, that is, so that the water will not flow directly through the compartment G by entering perforations 12 when the washer is forced downwardly into the water, then 110

2
into the compartment G and finding exit through the perforations 13, and vice versa when the washer is moved upwardly but must circulate to some extent circumferentially in the compartment G before finding exit. Thus the water is caused to effectively gather some of the soap or cleansing medium in the compartment and distribute and circulate such in the tub or other receptacle in which the clothes are disposed both during downward and upward movement of the washer.

In use, the washer may be charged with the cleansing medium by disposing the washer with its head uppermost, as shown in Figure 2, and the closure F removed so as to introduce the soap, in cake or chipped form, or in flake or powdered form disposed in a sack or other device pervious to water. The closure F may then be replaced and the washer used in the manner similar to other manually operated washers. In a like manner, bluing may be distributed and circulated, the bluing be-

ing preferably disposed in a sack, such as 25 cake bluing.

Changes in details may be made without departing from the spirit or scope of my invention; but,

I claim:

20 A clothes pounder comprising a handle, a shell carried by said handle, and open at its lower end, a partition rigidly secured in said shell intermediate the depth of the shell and having a centrally disposed soap passage and a plurality of water passages disposed about the soap passage in spaced relation thereto and in spaced relation to each other circumferentially of the partition, said shell being provided with water passages 35 corresponding in number to the water passages of the partition and positioned above the partition in close proximity thereto and in staggered relation to the water passages in the partition, and a removable 40 closure for the soap passage.

45 JOHN R. MITCHELL.
